UNITED STATES PATENT OFFICE.

JOHN R. SPURRIER, OF BETHLEHEM, PENNSYLVANIA, ASSIGNOR TO ROLLER-SMITH COMPANY, A CORPORATION OF NEW YORK.

ELECTRIC SWITCH.

1,275,098.

Specification of Letters Patent.

Patented Aug. 6, 1918.

Application filed October 20, 1915. Serial No. 56,833.

To all whom it may concern:

Be it known that I, JOHN R. SPURRIER, a citizen of the United States, residing at Bethlehem, in the county of Lehigh and 5 State of Pennsylvania, have invented certain new and useful Improvements in Electric Switches, of which the following is a full, clear, and exact specification.

This application relates to improvements 10 in circuit breakers, and particularly to that class of circuit breakers which are automatically openable in the presence of abnormal conditions, even during the time when the operator attempts to manually 15 close the breaker. My invention also relates to an improved construction of circuit breakers of this type having a plurality of switch members which are simultaneously closed and which are simultaneously opened upon 20 the occurrence of an abnormal condition in any one of the several circuits controlled.

Among the objects of my invention are the attainment of simplicity in construction, durability in operation, certainty of operation 25 and convenience in closing or opening the breaker by the operator in this type of circuit breaker. Another object is the provision of a breaker of this type which will occupy small lateral space and be pleasing in appearance. Other objects and 30 advantages of my invention will be understood from the following description and accompanying drawings.

Figure 1 is a side elevation of one form 35 of circuit breaker embodying my invention, showing the breaker partly closed. Fig. 2 is a front elevation of the same. Fig. 3 is a side elevation of certain of the parts when the breaker is in open position. Fig. 4 is 40 a side elevation of certain of the parts when the breaker is in nearly closed position. Fig. 5 is a side elevation of the same parts as in Fig. 4 when the breaker is in fully closed position, Figs. 4 and 5 showing the 45 side elevations on the opposite side of the breaker from those shown in Figs. 1 and 3. Fig. 6 is a front elevation of a breaker embodying my invention having multiple switches, and in open position, certain parts 50 being broken away. Fig. 7 is a side elevation of the same, partly in section, and Fig. 8 is a detail view of certain elements.

Referring to Figs. 1 to 5, the breaker is shown mounted upon a base 1. The stationary terminal of the breaker is shown 55 made up of a laminated brush contact 2 having a stiff outer leaf 3 which projects beyond the other leaves of the brush and spring pressed outwardly by the spring 4. This contact is also provided with a yield- 60 ably mounted carbon shunt contact 5 as shown, all of these parts being secured to the base by a bolt 6 which also serves to conduct the current to or from this stationary contact through the switch-board to the conducting mains. The current is conducted to or from the movable element of the breaker 65 through the bolt 7, which supports and makes electrical connection with the lower end 8 of a conducting copper ribbon which 70 passes upwardly and forms a spool 9, the inner end of the copper ribbon forming the spool being connected to a square core piece 10, which is preferably of soft iron or steel. Also electrically connected to the core piece 75 10 are two conducting side plates 11, which in turn carry a U-shaped conducting part 12, which serves as the movable contact of the breaker and is adapted to engage the laminated stationary contact 2-3 when the 80 breaker is closed as indicated in Fig. 1. The upper end of the conducting part 12 rigidly supports the carbon shunt contact 13 which engages the shunt contact 5 when the breaker is closed. The core piece 10 is pivotally 85 supported on the shaft 14, which shaft is supported at its opposite ends by two side frames 15, 16, which in turn are mounted upon the base 1.

The element which serves to close the 90 breaker is made up of two side pieces 17, 18, which are pivotally mounted upon the shaft 19, which latter is supported in upwardly extending ends of the side frames 15, 16. The inner ends of the side pieces 17, 18 carry 95 a pivotally mounted roller 20, which in turn engages another roller 21 on the shaft 22, the ends of which shaft are supported in the two side pieces 11, above described. In open position of the breaker, the roller 20 is considerably below its pivotal support 19 as shown in Fig. 3 and the movable switch element of the breaker is forced outwardly by gravity and by a spring 21' on each side of

the spool 9 so that the roller 21 is forced against the roller 20 to the position shown in Fig. 3. Further outward position of the roller 21 from that shown in Fig. 3 is prevented by lugs 22' formed on each of the side pieces 17, 18, because of their engagement with the side frames 15, 16, as shown in Fig. 3. When the breaker is to be closed, the closing element, comprising side pieces 17, 18 and roller 20, is rotated about the shaft 19, so that the roller 20 engages the roller 21 by rolling contact and consequently gradually forces the movable switch element toward the stationary contact. The circuit is first closed by shunt contact 13 engaging shunt contact 5. This contact by reason of its yieldable support next permits the contact element 12 to engage the secondary leaf contact 3, the parts then occupying the position shown in Fig. 1. Continued rotation of the closing element will finally force the breaker to fully closed position at which time the movable contact element 12 is forced against all of the edges of the laminated brush 2, thus giving full contact of all conducting parts. In fully closed position the axis of roller 20 is slightly above the plane passing through the axis of roller 21 and the axis of the pivotal support of the closing element, which is the axis of shaft 19. This fully closed position of these parts is shown in Fig. 5. Movement of the roller 20 above the position shown in Fig. 5 is prevented by the adjustable screw 23, which is carried by a lug 24 extending from the side piece 18 of the closing element, the screw 23 impinging upon the side frame 16, as shown in Fig. 5, and so preventing further rotation of the closing element or further upward movement of roller 20 beyond that shown in Fig. 5. The closing element thus in itself serves as the means for locking the breaker closed, and consequently no latch or other means is necessary for locking the breaker closed and no such parts are provided in my preferred construction.

The manual control of the closing element of the breaker is effected by an operating handle 25, the inner end 26 of which is pivoted upon the shaft 19 being spaced from the side pieces 17, 18 of the closing element by spacing sleeves 27, 27 as shown in Fig. 2. Pivotaly mounted upon the arm of the operating lever upon the shaft 28 is a pawl 29 which has two upwardly extending parts 29, which embrace the arm of the operating lever on each side thereof respectively, so as to be pivotally supported on the shaft 28, on both sides of the arm. Each side of the pawl has an inwardly projecting extension or tongue 30, each of which separately engages an abutment carried on the inside of each of the side pieces 17, 18 of the closing element. In the form of construction

shown, each of these abutments consists of 65 a roller 31 mounted upon a stud shaft 32, the end of which stud shaft is riveted to the side piece of the closing element, so as to permit each of the rollers 31 to be freely rotatable upon its respective stud shaft for 70 the purpose of reducing friction of the parts.

The pawl also has an upward extension 33 on each side of the arm of the operating handle and which is adapted to abut against 75 a cross piece 34 of the operating lever. It also has a downwardly extending part 35 and is so weighted that when the parts of the breaker are in open position and when the handle 25 is raised upwardly about its 80 pivot, gravity will cause the pawl to swing on its pivotal support 28 so that the tongues 30 will be thrown into engagement with the rollers 31. In Fig. 3, all parts are shown in fully open position and the handle 25 is 85 shown dropped to its lowest position and having no operative connection with the above described closing element of the breaker. When the handle 25 is raised from the position shown in Fig. 3 upwardly about 90 the pivot 19 to the dotted line position, the pawl will swing by gravity about its pivot 28 causing the abutments 33 to come against the cross piece 34, and causing the extensions 30 each to engage its respective roller 95 31 as shown in dotted line position in Fig. 3. Instead of gravity causing the pawl to occupy this position, it is obvious that a spring may be used which will tend to throw the pawl to the dotted line position of Fig. 100 3. The breaker may now be closed by pulling the handle 25 downwardly, the pawl now being carried downwardly with the operating lever moving about the pivot 19. By reason of the extensions 30 engaging the 105 rollers 31 and the extensions 33 abutting against the cross piece 34, the pawl during this movement will force the rollers 31 and consequently force the closing element of the breaker, comprising the side pieces 17, 110 18, about the pivot 19 and consequently cause the roller 20 to be moved to the right and upwardly from the position shown in Fig. 3. If the movement is continued the parts will assume the position shown in Fig. 115 1 showing the partially closed position, and further movement of the operating handle 25 will cause the breaker to be fully closed and finally held in closed position by the roller 20 as described above, with reference to the closing and locking action of the closing element. The operating handle and pawl will then occupy the position shown in Fig. 5 in relationship to the closing element.

In order to automatically cause the opening of the breaker when the breaker is being closed during abnormal conditions, even though the operator attempts to close the

breaker by operating the handle, I provide automatic means for breaking the pawl engagement between the operating handle and the closing element of the breaker. For this purpose I provide an armature 36 which is pivoted to the two side frames 15, 16 by a bolt or shaft 37. The armature 36 is U-shaped having its two arms extended downwardly and approaching the iron core piece 10, one arm being located on each side of the breaker within the side frames 15, 16, as well shown in Figs. 1 and 2. The upper ends of the arms are united by a cross portion. This armature completes the magnetic circuit of the magnetism created by the passage of current through the spool 9, by conducting the magnetic flux from one end of the core piece 10 around to the opposite end, gaps being located between the ends of the armature 36 and the ends of the core piece 10. Fastened to one side of the armature 36 is a plate 38 shown partly in full lines and partly in dotted lines in Figs. 1 and 3, and in full lines in Fig. 2. The lower edge of the outer end of this plate 38 is shown as having notches 39. Upon one side of the extension 35 of the pawl is located a pin 40. On the opposite side of the armature 36 from that carrying the plate 38 is an extension 41. This extension is adapted to engage under certain conditions a downwardly extending projection 42 on the side piece 18 of the closing element.

Under normal conditions the lower ends of the armature 36 are some distance below the ends of the core piece 10, and in its lowest position abuts against the end of the adjustable screw 43 carried in a lug extending inwardly from the side frame 15 as well shown in Fig. 2. By adjusting the screw 43, the overload current through the breaker which may be caused to attract and raise the lower ends of the armature 36 may be predetermined for any desired minimum overload current. The armature 36 also has an extension 44 which is adapted to pass over the outer edge of the side frame 16 which serves as a calibrating scale as indicated in Fig. 2. By adjustment of the screw 43, the extension 44 may be brought to any desired position with respect to the scale of amperage for which the breaker is calibrated.

Assuming the breaker to be open and the position of parts as shown in full lines in Fig. 3, then in order to close the breaker, the handle 25 is raised upwardly until the projections 30 of the pawl impinge against the rollers 31. The handle is then pulled downwardly which results in rotating the closing element and in causing the movable contact arm of the breaker to be moved to fully closed position as above described. If, however, during this closing movement an overload current exists, then before the breaker is fully closed, which condition is indicated in Fig. 1, the excessive current which is passed through the circuit breaker will cause the armature 36 to be attracted and bring one of the notches 39 against the pin 40 causing the pawl to be turned about its pivot and the projections 30 to be thrown out of contact with the rollers 31. This action breaks the thrust connection between the closing element and the operating lever and permits the movable contact element of the breaker to be immediately thrown to open position by pressure of the spring contacts, and by pressure of the springs 21 and by force of gravity. This results in turning the closing element about its pivot 19 to the position shown in Fig. 3. In order to attempt to close the breaker again, the handle 25 must again be raised so that the pawl parts 30 will again engage the rollers 31 in order to secure an operating connection between the handle and the closing element of the breaker. If the overload still exists, the action in opening the breaker will be the same as above described, the particular moment of opening depending upon how soon the overload current through the breaker attains sufficient amount to cause the releasing action. In some instances the action may occur when the carbon contacts only are engaged, in other instances, when the carbon contacts and leaf contact 3 are engaged, which position is illustrated in Fig. 1, and in other instances the closing movement may be carried still farther before the releasing action occurs. Thus in some cases during the closing movement the armature 36 may be attracted so quickly that the pin 40 will sometimes engage the first notch 39 as shown in Fig. 1, and in other cases the attraction may not occur until the breaker has been more fully closed, in which case the pin 40 will engage the next notch 39. Additional notches may of course be provided if desired. In some instances the engaging surface of the plate 38 with the pin 40 may be of such shape and the parts in such relationship that the notches 39 will be unnecessary, but in the form of construction shown I preferably provide these notches in order to prevent the magnetic attraction of the armature from being overcome by the closing force of the operator and instead of causing the pawl 30 to be forced out, might result in the magnetic force of attraction of the armature being overcome and forcing the armature to a position farther away from the core piece 10. With the provision of the notches, however, it will be seen that the leverage tending to throw the pawl out of engagement with the rollers 31 is greatly

increased. Thus, it will be evident from the position shown in Fig. 1 that exertion of any material pressure upon the handle 25 in a direction to close the breaker will assist 5 the unlocking of the parts by reason of the pin 40 being forced against the wall of one of the notches 39, and the force of attraction of the armature 36 is not so directly opposed. In some cases the releasing action 10 may be caused to take place by reason of the armature being attracted before the pin 40 reaches the outer edge of the plate 38 in which case when the pin strikes the outer edge, the breaking of the pawl connection 15 would be accomplished solely by the operator continuing downward pressure upon the handle 25.

Thus, it will be understood that under any overload or dangerous condition of the 20 circuit, it is impossible for the operator to hold the breaker closed, or to succeed in effecting the complete closure of the breaker under such a condition. If no overload or abnormal condition exists and the breaker is 25 fully closed, then when an overload or abnormal condition afterward does exist, the breaker will not be opened by merely breaking the pawl connection, but the projection 41 shown on the opposite side of the breaker 30 will then be brought into engagement, by the attraction of the armature, with the extension 42 from the side piece 18 of the closing element. This will result in forcing the roller 20 downwardly and thus free the movable contact arm, permitting it to be thrown 35 to open position. Thus it will be seen that at any time during the closing action or after the breaker is closed, the occurrence of an overload current will result in automatically opening the breaker, even though 40 the operator should attempt to hold the breaker closed. The breaker may be opened manually from closed position by merely raising the handle 25, the pin or rod 28 being 45 extended sidewise as shown in Fig. 2 sufficiently to reach under the outer end 45 of the side piece 17 of the closing element. Thus, it will be seen from Fig. 1 that an upward movement of the handle 25 would 50 cause the rod 28 to strike against the end 45 and throw the roller 20 downwardly and thus permit the breaker to be thrown to open position.

Referring now to Figs. 6, 7 and 8, the 55 construction of many parts is the same or similar to the construction already described, corresponding parts being given the same reference numerals. This circuit breaker comprises three switch elements, 60 each of the three switches comprising fixed contacts and movable contacts as above described and adapted to be connected in a three phase circuit or in any particular circuit connections as may be desired. Each

of the three switches has its respective controlling coil 9 and movable armature 36. On the passage of abnormal current through any one of the controlling coils 9 the corresponding armature will be attracted and cause all three switches to be opened automatically and simultaneously. 65

Extending along the front of the breaker is an insulating bar 50 to which is connected an element for closing each switch respectively. Each closing element comprises a 75 U-shaped piece seated against the underface of the bar and connected thereto by bolts 51. Each U-shaped element has its depending side frames 17', 18' pivoted on a shaft 19 extending between each of the supporting 80 side frames 15, 16, as in the construction of Figs. 1 to 5. Each U-shaped element also carries a roller 20 engaging a corresponding roller 21 as in the construction previously described. When the bar 50 is moved downwardly, all three of the movable switch elements will be moved to closed position simultaneously. 85

Movement of the multiple circuit breaker to closed position is accomplished by a 90 handle 25' connected to an insulating cross bar 52. This bar has connected to it three elements 26', each of which are pivoted respectively upon its shaft 19. Each element 26' has pivoted to it on a shaft 28 a pawl as 95 in the previously described construction, the form shown in Figs. 6 to 8 having tongues 30', weighted depending parts 35' and upward extensions 33'. The tongues 30' are adapted to engage abutments or rollers 31 100 carried on the side frames 17', 18', when the handle 25' is raised so as to secure an operative closing connection between the handle of the breaker and the closing element, in the manner previously described. All three of the pawls are mechanically connected together by rods 53, and insulating couplings 54. In view of this mechanical coupling of the parts, it is necessary for only one of the 105 pawls to be provided with tongues 30' for 110 engaging abutments or rollers 31. In the construction illustrated, the two outer parts of the breaker are shown without the rollers 31. The extensions 33' abut against pins 28' 115 on the elements 26' when the parts are in operative closing connection. The depending portion of each pawl is provided with a pin 40, each pin being adapted to be engaged by the edge of extension 38 from its 120 respective armature 36. Each of the side frames 17' of the closing element is provided with an extension carrying a roller 23', each of which abuts against the supporting side frame 15 when the breaker is in closed position, thus limiting the movement 125 of the closing element in one direction. The movement of the closing element in the opposite direction is limited by the lugs 22'

engaging the supporting side frames 15, as in the previously described construction. Each of the side frames 18' of the closing element of the breaker has an extension 42' and when the breaker is in closed position, the end of each extension 42' comes into proximity to an extension 41' on its respective armature, so that when the breaker is in fully closed position, the upward movement 10 of any one armature will cause its extension 41' to engage the end of extension 42' and pry the breaker open from its closed position.

In the closing operation of the multiple breaker, the handle is raised from the position shown in Fig. 7 until the handle element is coupled to the closing element by the tongues 30' engaging the abutments or rollers 31. The handle is then forced downwardly, which causes the closing element to simultaneously move all three switch elements toward closed position. If during the closing action, an abnormal condition exists in any one of the circuits, the corresponding armature will be attracted and by engagement with its corresponding pin 40 will result in turning the mechanically coupled parts illustrated in Fig. 8 and thereby break the connection with the closing 20 element, and will permit all three movable switch elements to simultaneously move to open position, giving an automatic release from the handle even though the operator continues to force the handle to the downward 30 position. The breaker can be again closed by the operator raising the handle so as to give an operative closing connection. If an overload occurs on any one of the circuits when the breaker is in fully 40 closed position, then the attraction of its corresponding armature will cause its extension 41' to engage its respective extension 42' and move the entire closing element so that the three rollers 20 are moved 50 downwardly below the rollers 21 and thus simultaneously permit all three switch elements to be moved to open position. Thus, automatic protection is secured at all times and simultaneous operation of the plurality 60 of switch elements is secured when an abnormal condition exists in any one or more of the several circuits controlled. The breaker may be opened manually at any time by merely raising the handle, such action 70 causing the handle levers 26' to engage the underside of the U-shaped closing elements under the cross bar 50 and thus force the closing element or elements away from the movable switch elements permitting their 80 movement to open position.

My invention may be embodied in various forms of construction without departing from the scope thereof.

Having thus described my invention, what

I declare as new and desire to secure by Letters Patent of the United States is:—

1. An electric switch comprising a movable switch element, a pivoted element for moving said switch element to closed position, a hand lever, disengageable operating means between said lever and said pivoted element operable in one direction for causing the closing of said switch element by the movement of said lever in one direction, and means whereby said pivoted element may be engaged directly by said hand lever by movement of said lever in the opposite direction to cause the opening of said switch element. 65

2. An electric switch comprising a movable switch element biased to open position, a pivoted element engaging said switch element for moving said switch element to closed position, an actuating lever, disengageable means for coupling said lever to 70 said pivoted element for producing an operative connection for causing the closure of said switch element by movement of said lever in one direction, and means whereby movement of said lever in the opposite direction causes it to directly engage said pivoted element and cause the opening of said switch element. 75

3. An electric switch comprising a movable switch element, an operating handle, 80 an element disconnected from said switch element for moving said switch element to closed position and holding said switch element closed by an overset locking position of said second named element, means for 85 disengageably coupling said handle to said second named element, and electro-magnetic means for breaking the coupling between 90 said handle and said second named element. 95

4. An electric switch comprising a movable switch element, a movable device disconnected from said element and for moving said element to closed position by pressure against said element and holding said switch element closed by an overset locking 100 position of said second named element, an actuating lever, means for disengageably coupling said lever to said device, and electro-magnetic means for breaking the coupling between said lever and said device. 110

5. An electric switch comprising a movable switch element, a device disconnected from said element for moving said element to closed position and for also serving to 115 lock said element in closed position, an actuating lever, disengageable means for coupling said lever to said device for producing an operative connection for causing the closure of said element by movement of said lever, and automatic means for uncoupling said means. 120

6. An electric switch comprising a mov-

able switch element, a device for closing said switch element and for also locking said element in closed position by an overset position of said device, an actuating lever, a pawl pivoted upon said lever for coupling said lever to said device and electro-magnetic means for disengaging said pawl.

7. A circuit breaker comprising a movable switch element, a device for moving said element to closed position and for also locking said element in closed position by an overset position of said device, an actuating lever, disengageable means for coupling said lever to said device for producing an operative connection for causing the closure of said element, and electro-magnetic means for uncoupling said disengageable means and for moving said device to unlock said element from its closed position.

8. A circuit breaker comprising a movable switch element, a device for moving said element to closed position and for also locking said element in closed position, an actuating lever, disengageable means for coupling said lever to said device, and electro-magnetic means for uncoupling said lever from said device during the closing movement upon the occurrence of an abnormal condition and for unlocking said element after said breaker has been closed.

9. A circuit breaker comprising a movable switch element, an actuating lever, disengageable means for producing an operative connection between said lever and said element for moving said element to closed position, a controlling winding, and an armature having a series of notches adapted to be engaged by said disengageable means for uncoupling said means.

10. A circuit breaker comprising a pivoted switch element, a roller carried thereby, a pivoted device having a roller adapted to engage the roller carried by said element for moving the latter to closed position and to lock the same in closed position by an overset position, an actuating lever, a pawl for coupling said lever and said device together, and electro-magnetic means for disengaging said pawl during the closing movement of the breaker and for unlocking the breaker from its closed position upon occurrence of an abnormal condition.

11. A circuit breaker comprising a support having two side frames, a movable switch element pivoted between said frames, a device for moving said element to closed position and for locking said element in closed position also pivoted between the said side frames, an actuating lever pivoted between said side frames, a pawl for coupling said lever to said device, and electro-magnetic means for disengaging said pawl dur-

ing the closing movement of the breaker and for moving said device from its locking position after the breaker has been closed.

12. A circuit breaker comprising a plurality of pivoted switch elements, an actuating hand lever, a pivoted element for simultaneously moving said switch elements to closed position and locking said elements in closed position, disengageable means for producing an operative connection between said lever and said element, and automatic means for causing the simultaneous opening of all of said switch elements by disengaging said first named means upon the occurrence of an abnormal current in any one of the circuits controlled by said switch elements during the closure of the circuit breaker and for also causing the opening of said switch elements after the circuit breaker has been fully closed.

13. A circuit breaker comprising a plurality of pivoted switch elements, a single device for forcing to and also locking said elements in closed position, a handle, disengageable means connecting said handle with said device, and means automatically responsive to an abnormal current in any one of the circuits controlled by said elements for uncoupling said handle from said device during the closing movement of the breaker and for forcing said device from locking position to simultaneously open said elements upon the occurrence of an abnormal current in any one of said circuits after the breaker has been fully closed.

14. A circuit breaker comprising a plurality of pivoted switch elements, an element for simultaneously forcing said elements to closed position, an actuating lever and handle, disengageable means between said lever and said element for securing an operative connection for closing said switch elements by the movement of the handle in one direction and for causing the opening of the breaker by direct engagement of said lever with said element by movement of said handle in the opposite direction, and means for automatically disengaging said disengageable means during the closing movement of the breaker for causing simultaneous movement of said switch elements to open position upon the occurrence of an abnormal current in any one of the circuits controlled by said switch elements.

15. A circuit breaker comprising a plurality of movable switch elements, a pivoted device for simultaneously moving said elements to closed position, and for locking said elements in closed position by an overset position of said device, a pivoted handle, a pawl for securing an operative connection between said handle and said device during closing movement of the breaker, a plurality of electromagnetic devices corresponding re-

spectively with the circuits controlled by said switch elements, and means acted upon by each of said electromagnetic devices for disengaging said pawl during the closing 5 movement of the breaker upon the occurrence of abnormal current in any one of said circuits and for forcing said pivoted device from locking position after the breaker has

been fully closed upon the occurrence of an abnormal current in any one of said circuits. 10

In testimony whereof I affix my signature, in presence of two witnesses.
